US0D1105423S

(12) **United States Design Patent** (10) **Patent No.:** **US D1,105,423 S**
(45) **Date of Patent:** **** Dec. 9, 2025**

(54) **PORT SYSTEM**

(71) Applicant: **Whisper Medical, Inc.**, Mountain View, CA (US)

(72) Inventors: **Martin S. Dieck**, Palo Alto, CA (US); **Soren Thompson**, New York, NY (US)

(73) Assignee: **Whisper Medical, Inc.**, Mountain View, CA (US)

(**) Term: **15 Years**

(21) Appl. No.: **29/880,378**

(22) Filed: **Jul. 21, 2023**

(51) **LOC (15) Cl.** **24-02**

(52) **U.S. Cl.**

USPC **D24/129**

(58) **Field of Classification Search**

USPC D24/112–114, 127–131, 133, 186; D23/259–269

CPC A61M 39/1011; F16L 37/0841; F16L 2201/20; F16L 2201/60

See application file for complete search history.

(57) **CLAIM**

The ornamental design for a port system as shown and described.

DESCRIPTION

FIG. 1 is a perspective view of a port system;

FIG. 2 is a top view of the port system of FIG. 1;

FIG. 3 is a bottom view of the port system of FIG. 1;

FIG. 4 is a left side view of the port system of FIG. 1;

FIG. 5 is a right side view of the port system of FIG. 1;

FIG. 6 is a front view of the port system of FIG. 1; and,

FIG. 7 is a back view of the port system of FIG. 1.

1 Claim, 5 Drawing Sheets
